THE NORRIS PETERS CO., PHOTO-LITHO., WASHINGTON, D. C.

UNITED STATES PATENT OFFICE.

WILLIAM S. SHERD, OF NORTHFIELD, MINNESOTA.

STRAP-CLAMP.

SPECIFICATION forming part of Letters Patent No. 430,891, dated June 24, 1890.

Application filed March 31, 1890. Serial No. 346,033. (No model.)

To all whom it may concern:

Be it known that I, WILLIAM S. SHERD, a citizen of the United States, residing at Northfield, in the county of Rice and State of Minnesota, have invented a new and useful Strap-Clamp, of which the following is a specification.

The invention relates to improvements in clamps for hitching-straps and the like.

10 The object of the present invention is to provide a device adapted to be readily attached to a strap or portion of a harness and capable of securely clamping another portion of the strap or harness to obviate the necessity of tying the strap and the inconveniences and dangers attendant upon the same.

15 The invention consists in the construction and novel combination and arrangement of parts hereinafter fully described, illustrated 20 in the accompanying drawings, and pointed out in the claims hereto appended.

In the drawings, Figure 1 is a perspective view of a clamp constructed in accordance with this invention and shown applied in operative position. Fig. 2 is a perspective view 25 of the device detached from the strap. Fig. 3 is a longitudinal sectional view.

Referring to the accompanying drawings, 1 30 designates a clamp, which consists of a base-plate 2, provided at one end with a stationary jaw 3 and at the other end with a loop 4, by means of which the plate is secured to a strap, a sliding jaw 5, having a plate or shank 6 formed integral therewith, and a cam-lever 7, 35 adapted to operate the sliding jaw and lock the same when clamping a strap. The base-plate 2 is constructed of suitable metal and is provided intermediate of its ends with a pair of ears 8, that are oppositely disposed and 40 formed integral with the plate 2, and have pivoted between them the cam-lever 7, the cam-face 9 of which is arranged to engage the sliding jaw 5 to lock the clamp and to engage a shoulder 10 to carry the sliding jaw out of 45 engagement with the strap. The plate or shank 6 of the sliding jaw 5 is provided with a slot 11, in which is arranged a screw 12, that limits the movement of the sliding jaw, and its threaded end engages a threaded perforation 50 of the plate 2. The cam-lever 7 has its arm 13 provided with a screw 14, which, when the

lever engages the sliding jaw, rests upon the head of the screw 12 and prevents the arm 13 of the lever coming too close to the shank of the sliding jaw and maintains the cam-face in 55 engagement with the sliding jaw and prevents the said cam being forced outward beyond the sliding jaw. By this construction a strap is readily clamped and secured in place without necessitating the tying of knots, which is 60 inconvenient.

The clamp may be attached to the ring which connects the lazy-straps with the crupper-strap and the back-strap, and the end of a hitching-strap can be secured to the clamp, 65 and the necessity of passing the strap through the terrets and tying the same is obviated. The clamp may also be attached to a hitching-strap, as illustrated in the accompanying drawings, and the clamp is arranged a sufficient distance from the end of the strap to 70 permit the latter to be passed around a post and secured by the clamp, which will prevent the strap slipping down the post and pulling upon the bit and annoying the animal, as is 75 the case where straps are tied to posts having no rings.

From the foregoing description and the accompanying drawings the construction, operation, and advantages of the invention will 80 be readily understood.

What I claim is—

1. A clamp for harness, comprising the plate 2, having a loop to receive a strap, and provided with a stationary jaw, the sliding jaw, 85 and the cam-lever arranged to engage and operate the sliding jaw, substantially as described.

2. A clamp for harness, comprising the plate 2, having a loop to receive a strap, and provided at one end with a stationary jaw and at the other end with a loop, and having intermediate of its ends a pair of ears 8, the sliding jaw having the plate or shank 6, and the cam-lever pivoted between said ears and 95 arranged to engage and operate the sliding jaw, substantially as described.

3. A clamp for harness, comprising the plate 2, adapted to be secured to a strap and having a stationary jaw 3 at one end, and provided intermediate of its ends with a pair of ears 8, the sliding jaw having the shank or

plate provided with a shoulder 10 and a slot 11, the screw 12, secured to the plate 2 and engaging the slot 11, and the cam-lever pivoted between the ears 8 and arranged to enable 5 gage and operate the sliding jaw, and provided with a projection 14, substantially as described.

In testimony that I claim the foregoing as my own I have hereto affixed my signature in presence of two witnesses.

WILLIAM S. SHERD.
